UNITED STATES PATENT OFFICE.

GILBERT S. STROM, OF WHITE ROCK, MINNESOTA.

MACHINE FOR WELDING AND SHAPING PLOWSHARES.

SPECIFICATION forming part of Letters Patent No. 633,921, dated September 26, 1899.

Application filed December 15, 1898. Serial No. 699,356. (No model.)

To all whom it may concern:

Be it known that I, GILBERT S. STROM, a citizen of the United States, residing at White Rock, in the county of Goodhue and State of Minnesota, have invented new and useful Improvements in Machines for Welding and Shaping Plowshares, of which the following is a specification.

This invention relates to machines for welding and shaping plowshares; and it has for its object to provide a simple and efficient machine of the character described by means of which the plowshare may be accurately, securely, and expeditiously welded to the landside and by which the plowshare may be shaped as desired without liability of injury to the weld.

To these ends my invention consists in the features and in the construction, combination, and arrangement of parts hereinafter described, and particularly pointed out in the claims following the description, reference being had to the accompanying drawings, forming a part of this specification, wherein—

Figure 1 is a perspective view of my improved welding-machine. Fig. 2 is a top plan view thereof, partially in section; and Fig. 3 is a vertical sectional view.

Referring to the drawings, the numeral 1 indicates the bed or base of the machine. This bed may be secured to a bench, anvil, or the like by any suitable means, and, as shown, has a perfectly flat top to form a straight and level seat or support for the parts to be welded and shaped. Formed with or secured to the bed 1 is a standard 2, which, as shown, is arranged at an angle of about forty-five degrees to the longitudinal axis of the bed. Formed on the opposite edge portions of the inner face of the standard 2 at a suitable distance above the bed are two lugs 3, the inner or adjacent faces of which are inwardly beveled or dovetailed, as indicated at 4. Arranged to slide vertically between the lugs 3 is a platen 5, which is beveled or dovetailed on its opposite edges 6 to correspond to the dovetailed faces of the lugs between which it slides. Pivoted on the inner face of the standard 2 above the platen 5 is a cam 7, having an eccentric curved portion 8 and a socket-arm 9, in which is adapted to be inserted a lever or handle 10. Formed on

the inner face of the cam 7 is a groove 11, that is curved to correspond to the configuration of the edge or periphery of the eccentric portion 8 of the cam. A vertical groove 12 is formed on the face of the standard adjacent to the cam, in which is arranged to move vertically a U-shaped link 13, one end 14 of which is loosely fitted in the groove 11 in the cam and the other end 15 of which is fitted in a recess 16, formed in the inner face of the platen 5. The link thus forms a loose connection between the cam and platen and operates to lift the platen when the lever or handle 10 is raised. The bottom 17 of the platen 5 is curved, as shown, to correspond to the curvature of the front upper portion of the plowshare to be welded and shaped, and the upper edge of said platen is provided with a shoulder 18, against which the cam 7 is adapted to operate to depress the platen.

Adjustably arranged on the bed 1 of the machine is an anvil 19, having a straight inclined forward edge 20 adjacent to and parallel with the inner face of the standard 2. The upper face 21 of the anvil 19 is slightly concaved and inclined downwardly and outwardly to correspond to the shape of the under side of the plowshare, while the inclined or beveled edge 20 thereof is adapted to fit the inner face of the landside of the plowshare. The anvil is provided with two longitudinal slots 22, formed one in advance of the other, through which pass bolts 23, or other suitable guides, that are fixed in the bed 1. The anvil 19 is thus free to be moved in a right line toward and from the standard 2, the arrangement being such that the inclined edge 20 of the anvil is always parallel to the inner face of the standard. Pivoted to the bed 1 in rear of the anvil 19 is a cam 24, provided with a peripheral flange 25 and also provided with a socket 26, in which is adapted to be fitted a handle 27. On the rear end of the anvil 19 is formed a downwardly-projecting hooked lug or finger 28, that takes over or overlaps the peripheral flange 25 of the cam, as most clearly shown in Figs. 1 and 2 of the drawings. The edge or periphery of the cam is in operative contact with the rear end of the anvil, and it will readily be understood that by turning the cam in the proper direction the anvil will

be projected toward the standard with great force. By turning the cam in the reverse direction the flange 25 of the cam will rotatively engage the finger 28 and retract the 5 anvil.

Adjustably arranged on the bed 1 opposite the anvil is a clamp consisting of a flat metallic plate 29, the inner end of which is inwardly beveled or undercut, as at 30. The plate 29 10 is longitudinally slotted, as at 31, and passing through said slot and through the bed 1 is a bolt 32, over the upper threaded end of which is fitted a washer 33 and nut 34, by means of which the plate is fixed in its adjusted position.

The operation of my improved machine is as follows: The plowshare and its landside which are to be welded together are heated to the proper heat for welding, and the landside 20 is then placed on the bed of the machine with its outer face resting against the inner face of the standard 2. Then by turning the cam 24 in the proper direction the landside is forcibly pressed against the face of the standard by the straight inclined edge 20 of the anvil 19, thus pressing out the inner and outer faces or opposite sides of the landside perfectly straight. The plowshare is then placed in position with its outer edge resting 25 under the undercutedge of the clamp 29, the latter having first been adjusted and fixed in the proper position, and its inner and forward edge resting on the upper edge of the landside. The cam 7 is then turned by depressing the lever 10, thus forcing down the platen 5. As before stated, the lower edge 30 17 of the platen is shaped to correspond to the configuration of the landside, and when the platen is forced down on the plowshare by the cam the plowshare and landside are pressed together with great force and are held until they become thoroughly welded. The same pressure that operates to weld together the plowshare and landside also gives to the plowshare its proper curvature at its forward edge 35 and presses out the under side of the landside perfectly flat and level. With a hammer the plowshare may be then hammered out on the anvil until it has been accurately 40 shaped, after which the lever 10 is raised, thus lifting the platen, the cam 24 is turned to withdraw the anvil, and the finished plowshare removed.

The flat surface of the bed 1 gives to the 55 landside and plowshare a perfectly straight edge on their under side, while the inclined faces of the anvil and standard give perfectly straight faces to the opposite sides of the landside. The cam forces the platen down upon 60 the plowshare with exceeding power, effecting a perfect weld, while the concaved and inclined upper face of the anvil affords a firm support for the plowshare, whereby the latter

may be truly shaped by hammering with ease and despatch and without liability of rupturing or injuring the weld. 65

Having described my invention, what I claim is—

1. In a machine for forming plowshares, the combination with a bed having an upright 70 standard provided with a vertical face diagonal to the length of the bed, of an anvil adjustably arranged on the bed and adapted to be moved toward and from the standard and having a straight edge substantially parallel 75 to the diagonal face of the standard, means for forcing said anvil toward the standard to press the landside between the adjacent faces of the anvil and standard, a platen arranged to move vertically in ways on the standard 80 and having its lower edge formed to correspond to the configuration of the plowshare, and a cam for forcing said platen downward to press the edges of the plowshare and landside together, substantially as described. 85

2. In a machine for forming plowshares, the combination with a bed having an upright standard provided with a vertical face diagonal to the length of the bed, of an anvil adjustably arranged on the bed and adapted to 90 be moved toward and from the standard and having a straight edge substantially parallel to the diagonal face of the standard, a platen arranged to move vertically in ways on the standard, a cam pivoted to the standard above 95 the platen and engaging the upper side of the latter, said cam having an eccentric groove formed on its inner face, and a U-shaped link vertically movable in a groove formed in the standard and having one of its ends loosely 100 fitted in the eccentric groove in the cam and its opposite end fitted in a recess in the inner face of the platen, substantially as described.

3. In a machine for forming plowshares, the combination with a bed having an upright 105 standard provided with a vertical face diagonal to the length of the bed, of an anvil adjustably arranged on the bed and adapted to be moved toward and from the standard and having a straight edge substantially parallel 110 to the diagonal face of the standard, said anvil having its upper side shaped to correspond to the configuration of the plowshare, means for moving the anvil toward the standard, a platen arranged to move vertically in ways on 115 the standard, means for forcing the platen downward, and a laterally-adjustable clamp on the bed opposite the anvil, substantially as described.

In testimony whereof I have hereunto set 120 my hand in presence of two subscribing witnesses.
